DONNING MECHANISM FOR RING SPINNING,
DOUBLING, AND TWISTING MACHINES

James Jackson Haythornthwaite and Thomas Highton, Accrington, England, assignors to T. M. M. (Research) Limited, Rossendale, England

Application November 22, 1950, Serial No. 197,162

Claims priority, application Great Britain
December 13, 1949

7 Claims. (Cl. 57—52)

1

This invention is concerned with ring spinning, doubling and twisting machines, particularly though not exclusively such machines as incorporate the doffing mechanism which forms the subject of co-pending United States Patent Application Serial No. 195,961, filed November 16, 1950, now patent No. 2,582,696, the object of the invention being to provide an improved apparatus for doffing the empty tubes, spins or like bobbins upon the spindles preparatory to the commencement of a fresh spinning operation after the removal of the previously completed yarn packages. Such improved doffing apparatus will be applicable to machines in which the relative reciprocatory motion between the spindles and the rings necessary for the formation of the yarn packages is effected by raising and lowering the spindle rail in relation to a stationary ring rail, or by reciprocatory movement of the ring rail in relation to a stationary spindle rail, or by a combined movement of both these elements in opposite directions.

In a ring spinning, doubling or twisting machine according to the invention, we provide in relation to each spinning unit a holder for releasably supporting an empty tube, spin or equivalent bobbin, said holder being movable from a loading position to the doffing position in which, when the spindle is raised to its uppermost position relative to the ring, or when the ring is lowered to its lowest position relative to the spindle, a tube or the like held by said holder will receive the spindle and be engaged by the latter in driving relationship, and means for returning said holder to the loading position.

A plurality of said tube holders, each relating to the spindle of a machine or of a unitary section thereof may be mounted for collective movement, either by manually actuated means or through mechanism operated in timed relationship with the package building mechanism.

In order that the nature of the invention and the manner of its performance may be more clearly understood, reference is made in the ensuing description to the illustrations, contained in the accompanying drawings, of the application of an improved doffing apparatus to a ring spinning machine incorporating doffing mechanism such as that which forms the subject of the said co-pending United States Patent Application Serial No. 195,961, now Patent No. 2,582,696. In such doffing mechanism each spindle is furnished with a removable package carrier member designed to support the yarn package upon the spindle and to be retained together with the

2

yarn package in the doffing position by interceptor means which come into operation before the next relative downward movement of the spindles, said carrier member being provided with means for seizing and severing the yarn to permit the yarn package to be removed from the carrier member and doffed preparatory to the next operation of doffing a fresh set of empty bobbins or the like upon the spindles.

In said drawings, Fig. 1 is a front elevation of part of the machine, showing the doffing apparatus in the operative position. Fig. 2 is an elevation, partly in section taken on the line II—II of Fig. 1, Fig. 3 is a horizontal section taken on the line III—III of Fig. 2, and Fig. 4 is a similar view to Fig. 2, depicting an alternative embodiment of the invention. Fig. 5 is a diagrammatical transverse section through a spinning machine incorporating doffing mechanism as illustrated in Fig. 4, illustrating the means provided for reciprocating the spindle rails. The machine exemplified in the drawings is of the kind in which the spindle rails are reciprocated vertically in relation to stationary ring rails.

In the drawings, the reference numeral 1 indicates the ring rail, 2 the ring, 3 the traveller and 4 the spindle, of an individual spinning unit. The doffing mechanism provided in such case comprises a package carrier member 5 which is retained in the doffing position, i.e. in which it would support a yarn package so that the whole of it was located above the ring, by interceptor plates 6. The interceptor plates 6 are mounted on the lower side of the ring rail being supported with capacity for sliding movement in the direction of their lengths. Each plate 6 is supported and guided by headed screws 6a, whose shanks pass freely upward through longitudinally extending slots 6b of the plates and are threaded into the ring rail. The plates are formed with interrupting projections which may be moved in one direction to interrupting positions as shown in Figure 2 and in the opposite direction to clear positions. The structure is more fully shown and explained in Patent No. 2,582,696. The carrier member 5 mounts a yieldable catch 7 by which the yarn 8 is arrested preparatory to its severance by the blade 9 from the last coil of the yarn package which is to be doffed.

The present invention provides a series of holders 10 which are mounted on a common bar 11 carried by brackets 12 which are fixed upon a shaft 13 extending longitudinally along the front 55 of the machine, or of a unitary section thereof,

so that each such holder 10 serves a separate spinning unit. The holders 10 illustrated in the drawings are adapted for use in conjunction with yarn package tubes of plain tapering form which will fit sufficiently tightly over the spindle blade to provide an adequate driving connection between them when the spindle is rotated. Each holder takes the form of a U-shaped clip between the limbs 14, 14 of which a tube 15 is received, a spring-pressed plunger 16 mounted in one of the 10 limbs being effective to retain the tube firmly in the holder until the latter is retracted on completion of the donning operation as hereinafter described.

The shaft 13 is suitably mounted immediately 15 beneath the front of the ring rail 1, and it is capable of being partially rotated through a crank 13b which is fast upon it, when the full yarn packages have been doffed, between a position, indicated by dotted lines in Fig. 2, in which the holders 10 may be loaded with empty tubes 15 preparatory to the next donning operation, and the position shown in full lines in which the tubes 15 are supported above the package carriers 5, resting on the seatings 17 thereof, in axial alignment with the spindle axes. As soon as the tubes 15 reach this position, the spindles 4 are raised to the uppermost limit of their movement, each being received within its respective tube; the interceptor plates 6 are then retracted from 30 engagement with the package carriers 5, so that on their ensuing downward movement the spindles carry with them the package carriers 5 and tubes 15. When the spindles are set in motion to resume spinning, the package carriers 5 and tubes 15 rotate with them.

The severed end of the yarn 8 being still held in the catch 7, it is caused to be wound upon the tube 15 at the instant when the latter commences to rotate with its spindle, but when the package 40 is doffed after completion of the build, the original end of yarn is pulled out of the catch which, as will be understood, is at this stage also holding the end of yarn newly severed at the commencement of the doffing operation.

At the commencement of the downward movement of the spindles, the now empty tube holders 10 are swung downwardly into the loading position where they may be re-loaded before the next cycle of the donning operation commences. In this position the holders 10 are disposed in an attitude in which the machine attendant may most conveniently insert the empty tubes 15 into said holders.

In order that the tubes 15 may be supported the more positively in the holders 10, it is convenient to mount upon the bar 11, by means of a series of standards 18 fixed thereto, an angle-plate 19 which is equal in length to said bar 11 and which serves, when the holders are in the loading position, to provide a ledge or shelf 20 against which the free ends of the tubes make contact. When the holders are moved to the donning position, said plate 19 assists in preventing lateral displacement of the tubes due to vibration whilst still unsupported by the spindles.

The shaft 13 may be rotated between its loading position and the donning position, and vice versa, either manually by the machine attendant, or through the agency of automatic mechanism operating in timed relationship with the package-building mechanism.

When this form of doffing apparatus is applied to a machine having a reciprocating ring rail, the shaft 13 is mounted so as to be capable of 75

partaking of the movement of the ring rail, in order that the tubes 15 may be correctly presented to the tips of the spindles over which they are to be donned.

In the alternative embodiment of the invention which is illustrated in Fig. 4, the tube holders take the form of a cup-like socket 21, incorporating a spring-pressed ball 22 which is adapted to grasp the side of the tube 15 of which the tip is placed in said socket 21. The sockets 21 are mounted on levers 23 fixed to a rockable shaft 13a mounted in suitable supports (not shown) at a position adjacent the tips of the spindles when these are raised to the doffing position. The shaft 13a may be rocked through a crank 13c which is fast on the shaft. The loading position is in this case such that the empty tubes 15 are held in a horizontal position, as shown in chain-dotted lines, until the shaft 13a is rotated to bring them to the full-line position, in which they are suspended vertically over the spindles in alignment with the axes thereof. In this arrangement the yarn-guide 24 (or lappet-guide) by which during the spinning operation the yarn 8 is led from the front drafting rollers to a point vertically above the spindle tip, is conveniently carried on a bracket 25 which is fixed to the lever 23, in such fashion that when the holder is moved into the donning position the guide 24 moves with the lever 23 and is turned aside to draw the yarn to a position at the side of the spindle until the holder has been returned to the loading position, whereafter the guide 24 is restored to the operative position above the spindle tip.

As shown in Fig. 5, the spindle rails are reciprocated by means of endless chains 26 to which they are attached by means of brackets 27, and which are passed over spaced longitudinal shafts 28 carrying chain sprockets 29. Said chains also pass beneath sprockets 30 which are fixed upon idler shafts 31. In the donning apparatus at the left-hand side the holder 15 is shown in the loading position, whilst the holder of the donning apparatus at the right-hand side is depicted in the donning position.

What we claim as our invention and desire to secure by Letters Patent is:

1. In a ring spinning, doubling or twisting machine having a spinning unit which comprises a spindle and an associated ring, and mechanism for effecting relative vertical movements of the spindle on the one hand and the ring on the other, in combination, a holder for releasably supporting an empty tube, pirn, bobbin or the like, the holder supporting a tube in the donning position in axial alignment with the spindle so that said tube will be caused to surround and engage the spindle in driven relation thereto when the spindle and ring reach the relative position in which the spindle projects to its maximum extent through the associated ring.

2. A structure as set forth in claim 1 in which the tube holder comprises a U-shaped clip adapted to receive a tube between its limbs and a spring pressed plunger carried by one of the limbs and projected yieldingly toward the other for releasably retaining the tube until the latter is doffed.

3. A structure as claimed in claim 1, wherein the tube holder comprises a socket adapted to receive the uppermost end of a tube and has a spring-pressed ball or like resilient means for releasably retaining such tube until doffed, and in which holder moving means is provided which

comprises a rock shaft and an arm fast on the rock shaft in which the holder is secured.

4. A structure as claimed in claim 1, wherein the tube holder comprises a socket adapted to receive the uppermost end of a tube and has a spring-pressed ball or like resilient means for releasably retaining such tube until donned, and in which holder moving means is provided which comprises a rock shaft and an arm fast on the rock shaft in which the holder is secured, a yarn-guide or lappet-guide operatively connected with said arm and so constructed and arranged that when the holder is moved to the donning position the yarn is drawn by a lateral movement of said guide to a position at the side of the spindle and, when the holder is restored to the loading position the yarn-guide is returned to the operative position above the spindle tip.

5. In a ring spinning, doubling or twisting machine having a series of spinning units each comprising a spindle and an associated ring, a ring rail common to the spindles upon which the several rings are supported, and mechanism for effecting relative vertical movements of the spindles on the one hand and the ring rail on the 25

other, in combination, a holder for each spinning unit for releasably supporting an empty tube, pirn, bobbin or the like, the holder supporting a tube in the donning position in axial alignment with the spindle so that said tube will be caused to surround and engage the spindle in driven relation thereto when the spindle and ring rail reach the relation in which the spindle projects to its maximum extent through the associated ring carried by the rail.

6. A structure as claimed in claim 5 which includes means for moving the holders comprising a rockable carrier for the holders, said carrier being mounted with a common bar extending longitudinally of the machine.

7. A machine as claimed in claim 6 comprising, a plate equal in length to said common bar, and standards carried by the bar and affixed to the plate and supporting the plate in horizontal position, said plate serving to support the free ends of the tubes, pirns, bobbins or the like.
